(57) **CLAIM**

The ornamental design for a microfluidic device, as shown and described.

DESCRIPTION

FIG. 1 is a top view of a microfluidic device in accordance with the present disclosure.

FIG. 2 is a bottom view of the microfluidic device of FIG. 1.

FIG. 3 is a left side view of the microfluidic device of FIG. 1.

FIG. 4 is a right side view of the microfluidic device of FIG. 1.

FIG. 5 is a front view of the microfluidic device of FIG. 1.

FIG. 6 is a back view of the microfluidic device of FIG. 1.

FIG. 7 is a top, left side, front view of the microfluidic device of FIG. 1.

FIG. 8 is a top view of another embodiment of a microfluidic device in accordance with the present disclosure.

FIG. 9 is a bottom view of the microfluidic device of FIG. 8.

FIG. 10 is a left side view of the microfluidic device of FIG. 8.

FIG. 11 is a right side view of the microfluidic device of FIG. 8.

FIG. 12 is a front view of the microfluidic device of FIG. 8.

FIG. 13 is a back view of the microfluidic device of FIG. 8;

and,

FIG. 14 is a top, left side, front view of the microfluidic device of FIG. 8.

The broken lines in the Figures depict environmental subject matter that forms no part of the claimed design.
